(57) **CLAIM**

We claim the ornamental design for a micro weather sensor,
as shown and described.

DESCRIPTION

FIG. 1 is a top, front and left side perspective view of an
ornamental design for a micro weather sensor;

FIG. 2 is a front elevational view thereof;

FIG. 3 is a back elevational view thereof;

FIG. 4 is a left elevational view thereof;

FIG. 5 is a right elevational view thereof;

FIG. 6 is a top plan view thereof; and,

FIG. 7 is a bottom plan view thereof.

The broken lines illustrate portions of the micro weather
sensor that form no part of the claimed design.
